UNITED STATES PATENT OFFICE.

JOSEPH G. KITCHELL, OF HADDAM, CONNECTICUT.

PICTURE AND PROCESS OF MAKING THE SAME.

1,144,964.

Specification of Letters Patent. Patented June 29, 1915.

Application filed December 24, 1913. Serial No. 808,582.

To all whom it may concern:

Be it known that I, JOSEPH G. KITCHELL, a citizen of the United States, and a resident of Haddam, county of Middlesex, State of Connecticut, have invented certain new and useful Improvements in Pictures and Processes of Making the Same, of which the following is a specification.

This invention relates to new and improved art products—pictures and the process of making the same.

In carrying out my invention an image, sketch or picture is produced in monochrome or varichrome on one medium or support and in varichrome upon another medium, or upon the different sides of the same medium, the tints, colors or tones being, in certain cases, veiled, as it were, by one medium which softens the harshness of the colors, blending and diffusing them in a most pleasing and harmonious manner resulting in an artistic effect, truthful to nature. By use of the word varichrome, I mean changing colors, selective colors, various colors, different or many colors—the combination of various colors or shades.

In general terms the process consists in making a drawing or sketch or design in pen and ink, pencil, crayon, or in any other suitable manner, upon a suitable thin fabric such as paper, linen, silk or celluloid of such a character that it is more or less transparent or translucent. Upon another medium of a heavier and denser nature, and in some instances preferably rigid and opaque such as porcelain, glass, celluloid, wood, cardboard, heavy paper or any other prepared or suitable material, preferably white in most instances, and suitable to carry water colors, oil or anilin colors, pastel, ink or any other character or nature of color, I outline generally first in monochrome the contours and principal details of the design or picture as borne upon the thin fabric and of the exact size and in exact register with the same. I then color the details of the design on the rigid medium or support so as to give correct color values to the design. Next the thin fabric or medium bearing the design is superposed over the color design on the thick preferably opaque support, keeping the two designs in correct register by any suitable means. The two mediums may be held in place by sheets of glass, or if desired, they may be closely se-

cured together by means which will cause them to stick or adhere to each other.

I have shown certain features of my invention in the accompanying drawings, it being understood that said drawings are merely illustrative and that I am not confined to what is there shown and herein described in connection therewith.

Referring to the drawings: Figure 1 is a front view of a thin medium having thereon, the contours and principal details of an uncolored design or picture. Fig. 2 is a front view of a thicker medium with the same picture thereon in reverse position. Fig. 3 is a front view of Fig. 2, having the colors applied to the picture for the purpose of giving proper color values thereto. Fig. 4 is the finished picture with the picture bearing medium of Fig. 1 superposed upon Fig. 3 and in exact register therewith. Fig. 5 is a cross sectional view on line 5 of Fig. 4. Fig. 6 is a cross sectional view of a modified form, partly broken away.

On the drawing the part marked A represents the thin picture bearing medium such as paper, linen, silk or the like.

B represents the picture which in this case is the profile of a woman's face.

C is the thicker and rigid medium preferably opaque such as porcelain, glass, celluloid or the like.

B' is the profile of the same face as that shown in Fig. 1.

The part marked D represents one color, and D' another color applied to the picture shown in Fig. 2, for the purpose of giving correct color values, and B² represents the finished picture after the picture bearing medium A, shown in Fig. 1, has been superposed upon the thicker picture bearing colored medium, shown in Fig. 3. By this arrangement the color work is underneath the thinner medium carrying the picture in neutral or one color thus producing a very artistic result and one that is in harmony with art ethics. With the superposing of the thinner sheet or medium carrying all the delicate details and modeling over the medium carrying the colors there is no loss of modeling or detail, while at the same time there is avoided the necessity of extreme nicety of work in spreading, grading and blending the colors, these effects being produced by the veiling when the thinner sheet is placed over the thicker sheet carry-

ing the colors. It is evident that as the colors are not required to be placed on the thick or under medium with any amount of skill, it can be done very rapidly, with the result that a beautiful and artistic picture is produced at little cost.

In the reproduction of duplicate etchings, engravings, wood-cuts and other similar pictures, an impression in black or other monochrome may first be made upon the thinner medium, and this same picture may then be transferred by tracing, printing direct or by an offset impression onto the thicker sheet or medium so that the exact reproduction and correct scale will be duplicated in the same or different degree of intensity and ready for filling in with the colors.

In producing duplicates of photographs according to my invention, the medium that is to carry the colors may be sensitized and a print made for guidance, or the pictures may be made upon this medium in other ways. The process is particularly valuable in its application to photo-portraiture as the life semblance is greatly enhanced by the addition of correct color values and as the print from the original negative is softened and diffused by the glow of color which comes through it, little or no retouching is necessary and hence the characteristics of the face are more faithfully depicted and the modeling preserved.

In the duplication of pictures in great numbers the color work may be lithographed, or made by the three color half-tone process or by any other successful commercial method.

The resultant effects hereinabove described may be varied by the use of a tinted tissue carrying the picture and used as the veiling, or by varying the tint of the monotone itself, the lightness or heaviness of the ink deposit, or by varying the color treatment on the thick medium. In some cases the thinner medium is superposed over the thicker medium with the inked or penciled or printed side or surface of the thinner medium next to the thicker medium and in other cases that side will be uppermost or out. If the paper or thinner medium carrying the neutral impression and which is to act as a veiling, is too thick or insufficiently transparent, I may immerse or cover the same with certain chemical solutions like sodium calcite or an alcoholic solution of white gum shellac of the right consistency, suitable for making close union between the medium bearing neutral impression and that bearing the colors. If the medium after such application is too shiny or transparent, I render it less so by covering it with another solution, such as that used for retouching photo negatives, containing gum dammar and Canadian balsam.

Where in some cases the paper or medium carrying the outer or neutral impression is not smooth enough or it is undesirable to incorporate it in immediate contact with (stuck to) the under medium, or when it is not desired to place a sheet of glass outside the outer paper or medium which paper or medium would thus be subdivided between it and the under plane, I obtain closer and smoother contact by beveling the edges of the under medium, as at E, Fig. 6, (when it is like porcelain, etc.,) and then tightly pull the paper or medium across and fasten it on the back at F by any suitable means so that the under medium is thus practically pushed up to meet the outer medium and then permanently positioned there.

There are times when the nature of the effect desired, or the nature of the outer medium employed, or the climatic or atmospheric conditions prevailing make it desirable or helpful to moisten the outer medium or heat or at the same time moisten and heat it by direct steam or moist hot air and stretch it across the face of the under medium while in that condition.

Having now described my invention, what I claim as new and desire to secure by Letters Patent is:

1. The process of making a design or picture which consists in producing the contours and principal details of the same on a thinner transparent medium, producing merely the outlines of the picture on a thicker opaque medium only, giving the outline on the thicker medium proper color values, and superposing the thinner medium over the thicker medium with the designs in register.

2. The process of making a picture which consists in producing the contours and principal details of the design on a thinner sheet of transparent paper, producing merely the outlines of the picture on a thicker medium of opaque material, applying paint to the outlines on the latter medium only giving color values to the design, superposing the paper over the opaque material with the outlines of the design on each medium in correct register, and securing the two mediums together.

3. The process of making a picture which consists in producing the contours and principal details of the same on a thinner sheet of transparent paper, producing merely the outlines of the picture on a thicker medium of opaque material, applying paint to the thicker medium only to give the design proper color values, and superposing the paper over the opaque material with the inked side of the former uppermost and with the outline of the design on each medium in correct register.

4. A design or picture consisting of an opaque support having merely an outline of

a design or picture thereon and colors applied thereto, a thinner transparent sheet carrying the contours and principal details of said design in monochrome, superposed upon said support with the outlines of the picture on each medium in proper register, the support and the sheet being secured together.

5. A picture or design consisting of a sheet of porcelain or other similar opaque support having a mere outline of a design or picture thereon with color values applied thereto, and a thinner sheet of transparent paper carrying the contours and principal details of the same design or picture in monochrome, superposed over and registering with the design or picture on the support, the said thinner sheet of paper being secured to said support.

6. A design or picture consisting of an opaque support having the mere outlines of a design or picture thereon in colors, a thinner sheet of transparent paper or other medium having the contours and principal details of the same design or picture in ink or other monochrome, superposed over and registering with the design or picture upon the support, the inked side of the medium being outermost and the medium being secured to the support.

In witness whereof I have hereunto set my hand in the borough of Manhattan, city and State of New York, this 16th day of December, 1913.

JOS. G. KITCHELL.

In presence of—

ISABEL R. RICHARDS,
JOHN J. RANAGAN.
